UNITED STATES PATENT OFFICE.

CLYDE AMBERT PIPPIN, OF CHICAGO, ILLINOIS, ASSIGNOR, BY MESNE ASSIGNMENTS,
TO CAMO CART COMPANY, OF CLINTON, ILLINOIS, A CORPORATION OF ILLINOIS.

FOLDING GOCART.

1,409,312.

Specification of Letters Patent. Patented Mar. 14, 1922.

Application filed February 24, 1919. Serial No. 278,638.

To all whom it may concern:

Be it known that I, CLYDE AMBERT PIPPIN, a citizen of the United States of America, and a resident of Chicago, Illinois, have 5 invented a certain new and useful Improvement in Folding Gocarts, of which the following is a specification.

This invention relates to folding go-carts of that kind in which the wheels and certain 10 other portions all fold into a compact bundle, and in which the folded parts are all enclosed within a rectangular box-like case which, when opened, forms the body of the go-cart.

15 Generally stated, the object of the invention is to provide a novel and improved folding go-cart of the foregoing general character.

Some special objects of the invention are to 20 provide a construction whereby the handle by which the box-like case is carried, when the go-cart is folded, is adjustable or operable to control the folding and unfolding of the wheels; to provide a construction 25 whereby a folding section of the box-like case forms a foot-rest when the go-cart is unfolded; to provide a construction whereby a telescoping and folding pole is adapted to be folded into a seating cavity within the 30 box-like case, and in which the pole when thus folded is enclosed by a folding section of the case, which section forms the back or head-rest when the go-cart is unfolded; to provide a construction whereby a folding top 35 for the go-cart is provided which is adapted to fold into the seating cavity formed in the box-like case when the go-cart is unfolded.

It is also an object to provide certain other 40 novel features of construction and details and combinations tending to increase the general efficiency and the desirability of a folding go-cart of this particular construction.

To these and other useful ends the invention 45 consists in matters hereinafter set forth and claimed.

In the accompanying drawings—

Fig. 1 is a perspective of the folding go-cart completely folded, showing the rectangular box-like case which forms the body of the go-cart when unfolded or opened, and which forms the exterior of the bundle when the go-cart is folded.

Fig. 2 is a perspective of the structure 55 partially unfolded.

Fig. 3 is a perspective of the go-cart entirely unfolded, with certain portions broken away for convenience of illustration.

Fig. 4 is a rear elevation of the go-cart in unfolded condition, with certain portions 60 shown broken away for convenience of illustration.

Fig. 5 is a longitudinal section of the go-cart in unfolded condition.

Fig. 6 is a cross section of the go-cart when 65 entirely folded.

Fig. 7 is a section on line 7—7 in Fig. 6.

Fig. 8 is a hinged fragmentary detail view 70 of the telescoping and folding pole which is provided for pulling the go-cart.

Fig. 9 is a longitudinal section of a portion 75 of said pole.

Fig. 10 is a longitudinal section of the body portion of the go-cart, in unfolded condition, showing the folding top which is attachable to the go-cart when desired.

Fig. 11 is a detail section on line 11—11 in Fig. 12.

Fig. 12 is an enlarged detail fragmentary view of a portion of one of the folding braces 80 that are employed to connect the hinged back or head-rest with the body of the vehicle.

Fig. 13 is a view similar to Fig. 6, showing 85 the manner in which the folded top is foldable into the box-like case which forms the body of the entire structure.

As thus illustrated, the rectangular and box-like case which forms the body of the go-cart is composed of a hinged side wall section 1, a fixed top wall 2, fixed end walls 90 3, hinged end walls 4, a hinged side wall composed of two sections 5 and 6 which are hinged together at 7, and a hinged top wall 8, the latter and the fixed wall 2 combining to form the top of the satchel-like case, when 95 the latter is entirely closed; and the bottom of the case is formed by a fixed section 9 and a hinged section 10, the section 5 being hinged at 11 to the edge of the section 9, and the section 10 being hinged at 12 to the other 100 edge of the section 9, and in this way the two sections 9 and 10 form the bottom of the case when the latter is entirely closed. The sections 6 and 8 are hinged together at 13 and the section 8 has catches or suitable devices 14 to engage the catches 15 on the section 2, which are like those used on an ordinary satchel or suitcase, and whereby the case is held in closed condition. The two 105 walls 3 are connected by rods 16 and a flexi-

ble seat 17 is fastened to the wall 2 at 18 and extends over these rods to a point where it is fastened at 19 to the wall 9 previously described, thereby providing a suitable seat. 5 The section 10 is provided with projections 20 which engage the slots 21 in the section 5, when the go-cart is unfolded, and a yoke 22 is rigidly secured to the folding section 10 of the case. This yoke 22 forms a part of 10 the pole for pulling the go-cart, being provided at its center with a fixed bracket 23 which has a recess 24 for receiving the edge portion of the section 8, whereby the latter and the section 6 and the section 5 form the 15 foot rest of the vehicle. The pivoted bracket 25 is pivotally supported by a bolt 26 inserted through the bracket 23, and a tubular section 27 of the tongue or pole is adapted to slide endwise in the guides 28 of this pivoted 20 bracket. The strap 29 is rigid with the bracket 25, and engages the pivot 26 previously described, and is formed with an opening 30 for the engaging end portion of the latch 31, which latter is pivoted at 32 on 25 said strap, being provided with a handle 33 for the operation thereof. The bracket 23 has an opening or notch 34 to receive the end of the latch 31, so that the bracket 25 will be locked in position to hold the pole in 30 position for use. A spring 35 is provided to yieldingly hold the latch 31 in engagement with the notch 34, but by pressing down on the handle 33 the latch will be operated to unlock the bracket 25, so that the latter can 35 be turned in the direction shown in Fig. 8, which is necessary in the folding of the go-cart. The tongue or pole comprises another tubular section 36 which slides in the section 27, and which is held in extended position by 40 a spring latch 37, in a manner that will be readily understood, and a third section 38 provided with a handle 39 forms the extreme or outer end of the pole. When the telescoping and folding pole thus provided is locked 45 in extended position, as shown in Fig. 9, the rear end portion 40 of the section 27 bears against the previously described folding section 8 of the case, so that this section 8 is clamped tightly against the bracket 23, thus 50 holding the foot-rest in position. When the pole is telescoped and folded as shown in Fig. 8, the section 10 can then be swung upward to bring the pole within the seating cavity formed between the two end walls 3, 55 and in this position the folded pole or tongue can then be enclosed by the folding side wall section 1 of the case. The section 5 is provided with legs 41 which are pivoted on the inner surface of the section at 42, and which 60 are connected by braces 43 with the brackets 44 on the section 9, and with this construction the legs 41 automatically fold into the position shown in Fig. 6 when the rectangular box-like case is closed; and these legs 41 65 then automatically unfold, and assume the

upright position shown in Figs. 2, 3 and 5, when the case is opened.

The section 1 forms the back or head rest of the vehicle, and is provided with braces which consist of arms 45 which are pivoted 70 on the rod 16, and which have their other ends pivotally connected at 46 with the short sections 47 of the braces. The sections 47 telescope within the sheet metal sections 48 of the braces, which latter are pivoted at 49 75 on the back or head-rest. The sections 47 are provided with depending lugs 50 which engage the shoulders 51 on the sections 48 to limit the extension of the sections 47 from the sections 48, when the go-cart is unfolded. 80 Ears 52 are provided on the ends of the sections 48 for the attachment of the folding top, as will hereinafter more fully appear. The braces thus provided assume the position shown in Fig. 6 when the go-cart is 85 folded and the case is closed. Arms 53 are pivoted on the other rod 16 and provided with notches 54 to engage the lower inturned end portions 55 of the guards 56 to hold the braces in any desired position, so that the 90 angle of the back or head rest can be changed.

The sections 4 of the case are hinged at 57 to the edges of the sections 3, and are provided with rigid bail-shaped brackets 58 upon which are suitably mounted the wheels 95 59 of the vehicle. When the case is entirely closed, the two wheels rest one upon the other, flatwise together, as shown in Fig. 7, and are enclosed by the sections 5, 6 and 8 of the case; but when the sections 4 are 100 swung outward, as shown in Fig. 4, the two wheels then assume upright positions to support the go-cart in the desired manner. The mechanism for folding and unfolding the wheels, and for holding them in operative 105 position, comprises a bar 60 which is pivoted at 61 upon the section 2 of the case, and which is provided with a folding handle 63 having cam portions 64 adjacent the pivots 65 thereof. The pivot 61 rigidly connects the bar 60 110 with another bar 66 which is inside of the case, and which is connected at its opposite ends by links 67 with the brackets 58 previously described, whereby the oscillating or twisting of the handle 63 in one direction 115 will throw the brackets 58 and the wall sections 4 outward, as shown in Fig. 4, thus bringing the wheels into the position necessary to support the vehicle on the ground. The handle 63 is then turned upward to cause 120 the cams 64 to bind tightly upon the plate 68 which is secured to the top of the case, and this locks the mechanism to hold the wheels in position. When it is desired to fold the go-cart, the handle 63 is tilted about its 125 pivot 65, and then it is twisted or turned or skewed in the opposite direction about the axis provided by its pivot 61, so that the wheels 59 are drawn into the case. Thus the folding and unfolding of the wheels is con- 130

trolled entirely by the handle by which the case is carried.

The section 1 can be provided with projections 69 to be engaged by pivoted hooks 70 on the section 10, when the case is closed, but any suitable catches or fastening devices can be employed for this purpose.

A flexible flap 71 is preferably attached to the back or head-rest at 72 in any suitable manner, and left loose to extend downward over the seat and foot-rest, in the manner indicated, if desired. This flap can be made of cloth or of any other suitable material.

A folding top is provided which comprises a pair of uprights 73 that are pivoted at 74 on the ears 52 previously described. The lower ends of these uprights are provided with horizontal heads having slots 75 therein, and front and rear arms or frame members 76 are provided with pivots 77 to engage said slots. The elements 73 and 76 are suitably connected together at their upper ends to form arch-like frame members, and the folding frame thus provided is equipped with a covering 78 of any suitable character, so that a sort of carriage top is provided. The pivots 74 are tight or stiff enough to hold the top in position for use, as shown in Fig. 10, but yield sufficiently to permit the top to fold into the position shown in Fig. 13, the pins 77 sliding toward each other in the slots 75 to reduce the folded top to a more compact form, because of the somewhat limited space within the case. It will be understood, of course, that the folding top thus provided will not interfere with the folding of the pole into the seating cavity, in the manner previously described, the top when folded leaving space to receive the pole, so that the latter will occupy the position shown in Fig. 6 when the case is closed. At such time, the flap 71, previously described, can be folded as shown in Fig. 13, and in this way the seating cavity will receive and enclose several portions of the folding go-cart structure.

If desired, the arms 53 can be provided with short end portions 79, and these end portions may be connected by springs 80 with the wall 2, as shown in Figs. 5 and 10, thereby to yieldingly hold the arms 53 in engagement with the lower portions 55 of the guards 56, for the purpose previously explained. These springs 80, however, are adapted to permit the arms 53 to be raised inside of the guards 56 when it is desired to fold the go-cart, or to change the angle of the back or head-rest.

It will also be seen that the portions 81 and 82, the latter being integral with the projections 20, are adapted to form supports for the case when the latter is entirely closed. When the case is opened, these portions then come together, as shown in Figs. 5 and 10, and the portions 20 enter the slots 21, as

previously described, so that the foot-rest is held rigidly in position. When the tongue or pole is swung into the position shown in Fig. 8, about its pivot 26, the section 8 of the case is thereby released, and the pole in telescoped condition can be moved endwise in the guides 28, so that the pole can be folded over into the seating cavity in the manner shown and described.

If desired, the brackets 58 may be provided with rearwardly extending arms 83 adapted to rest on the ground in rear of the vehicle, to prevent the latter from tipping over backward. These arms are pivoted on the brackets at 84, and have stops 85 that rest on the upper edges of the brackets to limit the upward movement of the curved rear ends of these arms. Links 86 are pivoted on said arms at 87 and are pivoted on the links 67 at 88, in any suitable manner, so that these arms 83 are automatically folded or swung around in a forward direction, when the wheels are folded into the bottom of the body, in order that these arms may occupy positions within the body. In other words, it will be seen that these arms 83 extend some distance in rear of the body, and that they would strike the lower edge of the section 2, when the wheels are folded, if the arms were rigid with the brackets; but by means of the pivots 84, and the connections 86 which automatically swing the arms 83 toward the front of the vehicle, the said arms are brought within the lower compartment in which the wheels are stored when the go-cart is entirely folded.

What I claim as my invention is:—

1. In a folding go-cart, a rectangular box-like case adapted to open and form the body of the go-cart, having a handle by which to carry the entire go-cart in folded condition, and wheels foldable into one side of the case and movable therefrom into position for use by adjustment of said handle.

2. In a folding go-cart, a rectangular box-like case adapted to open and form the body of the go-cart, and wheels foldable into one side of the case and movable therefrom into position for use, said case having a movable section for enclosing said wheels and adapted when unfolded to form a foot-rest for the front of the go-cart, a handle by which to pull the go-cart, and means to connect the handle to said foot-rest.

3. In a folding go-cart, a rectangular box-like case adapted to open and form the body of the go-cart, and a forwardly extending folding pole by which to pull the go-cart, said case having a movable section for enclosing said pole and adapted to form a back and head-rest when the case is opened, and another section forming a foot rest to which the pole is attached.

4. In a folding go-cart, a pair of wheels,

1 a rectangular box-like case adapted to open and form the body of the go-cart, having a hinged section that forms a back and head-rest when the case is opened, and having 5 end walls and a back wall forming a seating cavity into which certain portions of the go-cart are foldable and over which said back and head-rest is foldable to enclose said portions, and means to enclose the 10 wheels outside of said cavity.

5. In a folding go-cart, a rectangular box-like case adapted to open and form the body of the go-cart, having hinged sections forming end walls when the case is closed, 15 brackets on said walls, wheels carried by said brackets, and means to swing the walls and brackets to move the wheels into and out of the case.

6. In a folding go-cart, the combination 20 of a handle by which to direct the course of the go-cart, a pair of swinging brackets, wheels carried by said brackets, a handle by which to carry the go-cart when folded, and means whereby the wheels and brackets are 25 movable into folded position or into operative position by adjustment of said handle.

7. In a folding go-cart, a body having a seating cavity and a pole constructed to telescope and to fold sidewise in order that 30 it may then be folded into said cavity.

8. In a folding go-cart, a foldable foot-rest, a pole by which to pull the go-cart, and means on the pole to releasably support the foot-rest in position for use.

35. 9. In a folding go-cart, a rectangular box-like case adapted to open and form the body of the go-cart, having a hinged wall provided with a collapsible and forwardly extending pole for pulling the go-cart, and 40 having another hinged wall that forms a foot-rest, means to interlock the pole and the foot-rest, and means to interlock the two walls.

10. In a folding go-cart, a rectangular 45 box-like case adapted to open and form the body of the go-cart, having a seating cavity when opened, and a collapsible top adapted to fold into said cavity, said case having a hinged section which forms an outside wall 50 of said case and which serves as a back and head-rest when the case is open, and which encloses said top when the case is closed.

11. A structure as specified in claim 1, 55 said handle being pivoted to oscillate about an axis to control said wheel, so that by skewing the handle one way the wheels are pushed outward and by turning the handle the other way the wheels are pulled into the case.

60. 12. A structure as specified in claim 1, said foot-rest being composed of two narrow portions and one wide portion hinged to-

gether at their edges, with folding legs on the wide portion to support the go-cart against tilting forward.

65 13. A structure as specified in claim 3, having folding braces for said movable section, and means to adjustably engage said braces to hold the movable section in the desired position for use.

70 14. A structure as specified in claim 5, said means comprising an oscillatory member adapted to be skewed one way to throw the wheels outward and to be turned the other way to draw the wheels together, in combination with a forwardly extending handle by which to pull the go-cart.

75 15. A structure as specified in claim 7, said pole comprising a yoke hinged on the body, a long handle composed of telescoping sections, and a pivotal connection between the yoke and the handle.

80 16. A structure as specified in claim 8, said means comprising a bracket adapted to receive the edge portion of the foot-rest, and a pivoted portion to press this edge portion against the bracket when the pole is extended.

85 17. A structure as specified in claim 10, having telescoping and folding braces for 90 said back and head-rest, and means on said braces to support said top.

95 18. In a folding go-cart, a pair of swinging brackets, wheels supported independently of each other on said brackets, a body 100 into which the wheels and brackets are adapted to fold, rearwardly extending arms pivoted on said brackets and adapted to rest on the ground and prevent the go-cart from tipping backward, and connections to automatically fold said arms into position to enter said body when the wheels are folded together.

105 19. A structure as specified in claim 18, said connections comprising links connected to control the brackets, and means to connect said links with said arms, together with means for operating said links to fold and unfold the wheels.

110 20. In a folding go-cart, the combination of folding wheels, a pivoted handle by which to carry the go-cart in folded condition, and means whereby rotation of said handle serves to control the folding and unfolding of said wheels.

115 21. In a folding go-cart, the combination of folding wheels, a body which forms a box-like enclosure when the go-cart is folded, a handle on the upper side of said box-like enclosure by which to carry the go-cart in folded condition, and means operated by said handle to control the folding and unfolding of said wheels.

CLYDE AMBERT PIPPIN.
